COMBINED CONTAINER, DISPENSER, AND TRAY FOR SOAP

Anton Lang, 1724 W. Ball Road, Apt. 6,
Anaheim, Calif. 92804

Filed Apr. 4, 1966, Ser. No. 1,753

Term of patent 14 years

(Cl. D58—12.6)

FIG.1

FIG.5

FIGURE 1 is a perspective view of a combined container, dispenser, and tray for soap according to the present invention, the flap being in open position;

I claim:

The ornamental design for a combined container, dispenser, and tray for soap, substantially as shown and described.
